(57) **CLAIM**

The ornamental design for a chalk reel, substantially as shown and described.

DESCRIPTION

A portion of the disclosure of this patent document contains material to which a claim for copyright and trademark is made. The copyright and trademark owner has no objection to the reproduction of the patent document or the patent disclosure, as it appears in the U.S. Patent Office records, but reserves all other copyright and trademark rights whatsoever.

FIG. 1 is a first perspective view of an embodiment of my new design for a chalk reel;

FIG. 2 is a front elevational view thereof;

FIG. 3 is a back side elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a second perspective view thereof.

Uniform broken lines in the drawings, if any, represent unclaimed environmental matter. Randomly broken lines in the drawings, if any, represent contour lines. Surface shading in the drawings, if any, represents contour (flat or curved) and not surface ornamentation. The broken lines and surface shading in the drawings, if any, form no part of the claim.
